(57) **CLAIM**

The ornamental design for a light transmissive lens and frame for biometric sensor module, as shown and described.

DESCRIPTION

FIG. 1 is a top side perspective view of a light transmissive lens for biometric sensor module showing my new design;

FIG. 2 is a top view thereof;
FIG. 3 is a bottom view thereof, opposite the view shown in FIG. 2;

FIG. 4 is a bottom perspective view thereof;

FIG. 5 is a second bottom perspective view thereof;

FIG. 6 is a third bottom perspective view thereof;

FIG. 7 is a fourth bottom perspective view thereof;

FIG. 8 is a section view taken along line 8-8 in FIG. 3 illustrating an internal channel of the light transmissive lens;

FIG. 9 is a side view thereof;

FIG. 10 is a side view thereof, opposite the view shown in FIG. 9;

FIG. 11 is an end view thereof;

FIG. 12 is an end view thereof, opposite the view shown in FIG. 11;

FIG. 13 is a top side perspective environmental view thereof;

FIG. 14 is a bottom side perspective environmental view thereof;

FIG. 15 is a bottom environmental view thereof;

FIG. 16 is a bottom side perspective environmental view thereof;

FIG. 17 is a perspective view of the light transmissive lens for biometric sensor module, showing my new design in an exemplary in-the-ear device;

FIG. 18 is a top side perspective view of a light transmissive lens for biometric sensor module showing my new design, the shading representing a red and optically transmissive material;

FIG. 19 is a top view thereof;

FIG. 20 is a bottom view thereof, opposite the view shown in FIG. 19;

FIG. 21 is a bottom perspective view thereof;

FIG. 22 is a second bottom perspective view thereof;

FIG. 23 is a third bottom perspective view thereof;

FIG. 24 is a fourth bottom perspective view thereof;

FIG. 25 is a section view taken along line 25-25 in FIG. 20 illustrating an internal channel of the light transmissive lens;

FIG. 26 is a side view thereof;

FIG. 27 is a side view thereof, opposite the view shown in FIG. 26;

FIG. 28 is an end view thereof;

(Continued)

FIG. 29 is an end view thereof, opposite the view shown in FIG. 28;
 FIG. 30 is a perspective view of a light transmissive lens for biometric sensor module, showing my new design in an exemplary in-the-ear device;
 FIG. 31 is a top side perspective view of a light transmissive lens for biometric sensor module showing my new design;
 FIG. 32 is a top view thereof;
 FIG. 33 is a bottom view thereof, opposite the view shown in FIG. 32;
 FIG. 34 is a bottom perspective view thereof;
 FIG. 35 is a second bottom perspective view thereof;
 FIG. 36 is a third bottom perspective view thereof;
 FIG. 37 is a fourth bottom perspective view thereof;
 FIG. 38 is a section view taken along line 71-71 in FIG. 33 illustrating an internal channel of the light transmissive lens;
 FIG. 39 is a side view thereof;
 FIG. 40 is a side view thereof, opposite the view shown in FIG. 39;
 FIG. 41 is an end view thereof;
 FIG. 42 is an end view thereof, opposite the view shown in FIG. 41;
 FIG. 43 is a top side perspective view of a light transmissive lens for biometric sensor module showing my new design, the shading representing a red and optically transmissive material;
 FIG. 44 is a top view thereof;
 FIG. 45 is a bottom view thereof, opposite the view shown in FIG. 44;
 FIG. 46 is a bottom perspective view thereof;
 FIG. 47 is a second bottom perspective view thereof;
 FIG. 48 is a third bottom perspective view thereof;
 FIG. 49 is a fourth bottom perspective view thereof;
 FIG. 50 is a section view taken along line 83-83 in FIG. 45 illustrating an internal channel of the light transmissive lens;
 FIG. 51 is a side view thereof;
 FIG. 52 is a side view thereof, opposite the view shown in FIG. 51;
 FIG. 53 is an end view thereof;
 FIG. 54 is an end view thereof, opposite the view shown in FIG. 53;
 FIG. 55 is a top side perspective view of a light transmissive lens for biometric sensor module showing my new design;
 FIG. 56 is a top view thereof;
 FIG. 57 is a bottom view thereof, opposite the view shown in FIG. 56;
 FIG. 58 is a bottom perspective view thereof;
 FIG. 59 is a second bottom perspective view thereof;
 FIG. 60 is a third bottom perspective view thereof;
 FIG. 61 is a fourth bottom perspective view thereof;
 FIG. 62 is a section view taken along line 95-95 in FIG. 57 illustrating an internal channel of the light transmissive lens;

FIG. 63 is a side view thereof;
 FIG. 64 is a side view thereof, opposite the view shown in FIG. 63;
 FIG. 65 is an end view thereof;
 FIG. 66 is an end view thereof, opposite the view shown in FIG. 65;
 FIG. 67 is a top side perspective view of a light transmissive lens for biometric sensor module showing my new design, the shading representing a red and optically transmissive material;
 FIG. 68 is a top view thereof;
 FIG. 69 is a bottom view thereof, opposite the view shown in FIG. 68;
 FIG. 70 is a bottom perspective view thereof;
 FIG. 71 is a second bottom perspective view thereof;
 FIG. 72 is a third bottom perspective view thereof;
 FIG. 73 is a fourth bottom perspective view thereof;
 FIG. 74 is a section view taken along line 107-107 in FIG. 69 illustrating an internal channel of the light transmissive lens;
 FIG. 75 is a side view thereof;
 FIG. 76 is a side view thereof, opposite the view shown in FIG. 75;
 FIG. 77 is an end view thereof; and,
 FIG. 78 is an end view thereof, opposite the view shown in FIG. 77.

In the drawings, the broken lines illustrate portions of the article that form no part of the claimed design.
